US0D1113851S

(12) **United States Design Patent** (10) **Patent No.:** **US D1,113,851 S**
(45) **Date of Patent:** **** Feb. 17, 2026**

(54) **WIRELESS EARPHONE**

(71) **Applicant:** **Listening Wisdom (Nanjing) Technology Co., Ltd.**, Jiangsu (CN)

(72) **Inventor:** **Yingwei Wang**, Jiangsu (CN)

(73) **Assignee:** **Listening Wisdom (Nanjing) Technology Co., Ltd.**, Jiangsu (CN)

(**) **Term:** **15 Years**

(21) **Appl. No.:** **29/843,007**

(22) **Filed:** **Jun. 17, 2022**

(30) **Foreign Application Priority Data**

Dec. 17, 2021 (CN) 202130838039.1

(51) **LOC (15) Cl.** **14-01**

(52) **U.S. Cl.**

USPC **D14/223**; D24/174

(57) **CLAIM**

The ornamental design for a wireless earphone, as shown and described.

DESCRIPTION

FIG. 1 is a top, front, and left perspective view of a first embodiment of a wireless earphone showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, and left perspective view thereof a second embodiment of a wireless earphone, showing the claimed design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan elevation view thereof; and,

FIG. 14 is a bottom plan elevation view thereof.
